(57) CLAIM

The ornamental design for a vehicle steering-wheel cover, as shown and described.

DESCRIPTION

FIG. 1 is a front elevational view of a vehicle steering-wheel cover showing my new design, the rear elevational view being a mirror image;

FIG. 2 is a top plan view of FIG. 1,

FIG. 3 is a bottom plan view of FIG. 1,

FIG. 4 is a right side view of FIG. 1, the left side view being a mirror image,

FIG. 5 is a front elevational view of a second embodiment of the vehicle steering-wheel cover, the rear elevational view being a mirror image,

FIG. 6 is a top plan view of FIG. 5,

FIG. 7 is a bottom plan view of FIG. 4,

FIG. 8 is a right side elevational view of FIG. 5, the left side view being a mirror image,

FIG. 9 is a front elevational view of a third embodiment of the vehicle steering-wheel cover, the rear elevational view being a mirror image,

FIG. 10 is a top plan view of FIG. 9,

FIG. 11 is a bottom plan view of FIG. 9; and,

FIG. 12 is a right side elevational view of FIG. 9, the left side view being a mirror image.
